UNITED STATES PATENT OFFICE

JULES LINDAUER, OF PARIS, FRANCE

LACING DEVICE FOR CORSETS AND LIKE ARTICLES

Application filed November 9, 1928, Serial No. 318,114, and in France July 19, 1928.

The present invention relates to lacing devices for corsets, belts, bodices and like articles, and has chiefly for its object to facilitate the sliding of the laces in the eyelets.

According to the invention, each eyelet is inserted separately in an individual pocket which is open at the side for the passage of the lace, in such manner that the lace, at the point at which it passes through the eyelet, is not in direct contact with the garments situated above or below, or with the skin if the corset is worn in direct contact with the body. The said pockets are preferably soft, but they may be slightly stiffened by a suitable lining so as to avoid wrinkling, and are preferably formed by the suitably folded edges of the fabric of the corset and its lining, which cover both sides of an eyelet-carrying-band, each pocket being separated from the adjacent pocket by a substantial stitch which traverses the said eyelet-band and connects the folded parts of the main fabric and the lining.

The appended drawings which are given by way of example show an embodiment of the invention.

Fig. 1 is a plan view, with parts broken away, of a portion of a laced device according to the invention.

Figs. 2 and 3 are sections respectively on the lines 2—2 and 3—3 of Fig. 1.

In the embodiment herein represented, the device comprises an eyelet band formed of one or more layers of cloth 1, which is covered at the edge by a facing strip 2, bent around the layers 1. These two members are traversed by the metallic or other eyelets 3 and are connected together by three rows of stitches 4, 5, 6. The members 1 and 2 are placed between the main fabric 7 of the corset, which is folded at 8, and the lining 9 of the corset which is folded at 10. The folded parts of the main fabric of the corset and of the lining are held by the rows of stitches 11—12 situated near the outer edge. Stiffeners are disposed at 13—14. The several parts are also joined by rows of stitches 15, 16, 17. Between the eyelets, the said eyelet band 1, 2 and the folded parts of the main fabric and the lining of the corset are joined

by the heavy stitches 18, situated near the fold of said folded edges and which extend through said eyelet-carrying band and through only the inner, turned in portions of said folded fabric and lining respectively. In this manner, said stitches 18 are covered and hidden by the outer sheets of said fabric and lining respectively.

It will be further noted that said stitches are located between the line of centres of successive eyelets and the free edge of the eyelet carrying band.

Due to this method of construction, each eyelet is situated in a small pocket with flexible walls, through which is inserted the lace 20. This prevents all direct contact between the doubled up part of the lace at its passage through the eyelet and the garments placed either above or below the corset, and the lace will thus slide with much greater facility. It will be also observed that the eyelets are protected and concealed and that the lacing edge remains quite flat, and without an inconvenient thickness.

Obviously, the said invention is not limited to the constructional form herein described and represented, and for example I may employ all of the usual methods of strengthening by the use of layers of cloth. The stitches 18 may be replaced by a metal fastening, for instance rivets or very small eyelets.

The said invention is applicable not only to corsets, but also to bodices, belts, bust supporters and the like.

Having now described my invention, what I claim as new and desire to secure by Letters Patent is:

1. In a lacing device for corsets and like articles, two pieces to be laced, a folded edge of the corset fabric and a folded edge of the lining of each of said pieces, the turned-in portions of said folded edges facing each other, an eyelet-carrying perforated band between said turned-in portions of said folded fabric and lining of each respective piece and covered by said folded edges, means for fastening said fabric, lining and band together, and means for fastening said fabric, lining and band between said successive eyelets near the fold of said folded edges.

2. In a lacing device for corsets and like articles, two pieces to be laced, a folded edge of the corset fabric and a folded edge of the lining of each of said pieces, the turned-in portions of said folded edges facing each other, an eyelet-carrying perforated band between the said turned-in portions of said folded fabric and lining of each respective piece and covered by said folded edges, means for fastening said fabric, lining and band together, and short and heavy stitches for fastening together said folded over parts of fabric and lining onto the respective faces of the said band between said successive eyelets, near and within the folds of said folded edges, and between the line of centres of successive eyelets and the free edge of the eyelet carrying band.

3. Lacing device according to claim 1 wherein said means for fastening said fabric, lining and band between successive eyelets and near the fold of said folded edges extend through said eyelet-carrying band and through only the inner, turned-in portions of said folded fabric and lining respectively, whereby said means are hidden and covered by the outer sheets of said fabric and lining respectively.

4. In a lacing device according to claim 1, a row of stitching fastening together the inwardly folded and outer parts of said folded edge of said fabric, a row of stitching fastening together the inwardly folded and outer parts of said folded edge of said lining, said rows of stitchings extending over the whole height of the lacing device and running near the fold of said folded edges of said fabric and lining respectively.

5. In a lacing device according to claim 1, the feature residing in that said eyelet-carrying band comprises a strip of cloth, a covering strip of fabric folded over and enclosing said strip of cloth, rows of stitching fastening together said strip of cloth and said folded-over covering strip and running along the entire height of said strips, and eyelets fastened through said cloth and covering strips.

In testimony whereof I have signed my name to this specification.
